UNITED STATES PATENT OFFICE.

RAY H. EVERETT, OF NEW YORK, N. Y.

DESIGN FOR AN EMBLEM, BADGE, OR ARTICLE OF SIMILAR NATURE.

56,346.

Specification for Design.

Patented Oct. 5, 1920.

Application filed May 13, 1919. Serial No. 296,932. Term of patent 3½ years.

To all whom it may concern:

Be it known that I, RAY H. EVERETT, a citizen of the United States, a resident of New York, in the county of New York and State of New York, have invented a new, original, and ornamental Design for an Emblem, Badge, or Article of Similar Nature, of which the following is a specification, reference being had to the accompanying drawing, forming part hereof.

The figure is a plan view of an emblem, badge, or article of similar nature showing my new design.

I claim:—

The ornamental design for an emblem, badge, or article of similar nature as shown.

RAY H. EVERETT.
